UNITED STATES PATENT OFFICE.

GENEVIEVE PFEFFER, OF SAN JOSE, CALIFORNIA.

DESIGN FOR A DOLL.

51,559.

Specification for Design.

Patented Dec. 11, 1917.

Application filed September 24, 1917. Serial No. 193,055. Term of patent 3½ years.

To all whom it may concern:

Be it known that I, GENEVIEVE PFEFFER, a citizen of the United States, residing at San Jose, in the county of Santa Clara, State of California, have invented a new, original, and ornamental Design for Dolls, of which the following is a specification, reference being had to the accompanying drawing, forming a part thereof.

In the drawings, Figure 1 is a side elevation of the doll showing my new design.

Fig. 2 is a front elevation of the same.

I claim:

The ornamental design for a doll as shown.

GENEVIEVE PFEFFER.

Witnesses:

ROSE PFEFFER,
R. M. WRIGHT.
